tion of New York

Application May 22, 1946, Serial No. 671,577

6 Claims. (Cl. 23—175)

1

This invention relates to improvements in the manufacture of oleum and sulfuric acid.

The invention, its objects and advantages may be understood from the following description taken in connection with the accompanying drawing showing diagrammatically, apparatus in which a preferred embodiment of the improved process for making oleum may be carried out.

Referring to the drawing, numerals 11, 12, 13, 14, 15, 16 and 17 respectively indicate a sulfur vaporizer, a combustion chamber, a gas cooler, a filter and three converters of a multi-stage catalytic SO₂ oxidation operation. Vaporizer 11 may be any apparatus adapted to pressure operation such as a stationary unit into which sulfurous material is charged and burned to form SO₂ gas or a mixture of SO₂ gas and sulfur vapor. Combustion chamber 12 may be of suitable construction by means of which completion of combustion of sulfur is effected. Converters 15, 16 and 17 may be of any satisfactory design known in the art, the converters each being arranged to contain a catalyst such as a vanadium catalyst the activity of which is not adversely affected by the presence of moisture in the gas stream.

Undried air at atmospheric temperature is supplied to the process by a main blower 20 the pressure side of which communicates thru header 21 and valve controlled pipe 22 with the combustion chamber 12. By valved pipes 24 and 25, air may be introduced into conduits 27 and 28 which connect the converters and thru which the main SO₂ gas stream passes from the first to the second and from the second to the third conversion stages. Some of the air may be drawn from header 21 and forced by booster blower 30 into sulfur vaporizer 11 at pressure greater than that at which air is supplied to combustion chamber 12.

The SO₃ exit gas of converter 17 passes thru line 32 into the gas inlet connection 33 at the bottom of a tower 35 which may be designated as a sulfuric acid condenser and/or a wet SO₃ gas drier. Condenser-drier 35 comprises grille-work 36 arranged to support packing material 37, a plate 38 for distributing oleum liquor over the packing, and a gas exit pipe 39. Oleum effluent of tower 35 runs thru pipe 44 into a cooler 45. The suction side of a pump 50 communicates with the outlet of the cooler, and the pressure side of the pump is connected to pipe 51 by which oleum liquor may be fed to the top of tower 35 or drawn off thru conduit 53 to a subsequent phase of the process. Cooler 45, pump 50 and pipe connections 44 and 51 may be of any suitable design,

2

as known in the art, to facilitate control of temperature and quantity of the oleum liquor circulated over tower 35.

In carrying out the preferred embodiment of the invention, brimstone is continuously fed into a pool of molten sulfur maintained in the bottom of vaporizer 11. Admission of undried air at suitable pressure to the vaporizer is adjusted so that part of the sulfur is burned to generate sufficient heat to melt incoming sulfur and to vaporize the unburned balance of the sulfur. The gas mixture leaving the vaporizer is charged into the combustion chamber along with more than enough air from line 22 to effect oxidation of unburned sulfur to SO₂. The combustion chamber exit, heated to temperature in the neighborhood of 2000° F., comprises sulfur dioxide, oxygen, water vapor and nitrogen. In this embodiment, operation of the vaporizer and combustion chamber is controlled so as to produce a strong gas containing by volume not less than 10% and preferably not less than 12% SO₂. Oxygen content of the gas stream at this point may be in the range of 11 to 9% volume. In cooler 13, the gas stream is cooled down to close to but not below initial conversion temperature, e. g. to 780-825° F. If the gas stream contains suspended solids, such as impurities derived from the brimstone, a filter 14 may be employed, and the exit gas thereof, containing (dry basis) say 12% SO₂ and 9% oxygen, is introduced into converter 15 at temperature of about 800° F.

The exit of the first conversion stage may be heated by oxidation reaction to temperature of about 1160° F. and contain (dry basis) about 4.4% SO₂, 8.1% SO₃, and 5.3% oxygen. The converter exit carries a substantial amount of moisture brought into the process with the air and brimstone. Such a gas raises serious operating problems as to possible use between conversion stages of the usual tubular heat exchangers since, when handling a wet gas, substantial precautions must be taken with respect to heat transfferer design, materials of construction and mode of operation because of the marked tendency of H₂SO₄ to condense out of the gas stream and seriously corrode the transferrers. In the present process, the foregoing difficulties are overcome by effecting inter-stage cooling by means of cool undried air from blower 20 which air has the twofold function of cooling the gas stream down to temperature suitable for admission to the following conversion stage and supplying any additional oxygen needed for completion of conversion. Hence, the valve in line 25 is adjusted so as to reduce the tempera-

ture of the gas stream in line 21 to about 820° F.

The gas stream may leave the converter 16 at temperature of about 945° F. and, by regulation of the valve in air line 24, sufficient air may be introduced into conduit 28 to lower the temperature of the gas stream to about 780° F. The gas stream exits converter 17 at temperature of about 800° F., and a typical converted gas may contain by volume (dry basis) 7.1% SO₃, 11.0% oxygen, and nitrogen, overall SO₂ conversion being about 98%. In a representative operation, the converted gas may contain from 0.16 to 0.64 gram per cubic foot of H₂O, i. e., enough water to unite with 10 to 40% of the total SO₃ to form H₂SO₄, depending upon geographical or seasonable conditions and moisture content of the brimstone. In preferred practice of the invention, the SO₃ gas employed contains preferably not more water than needed to unite with the 40% of the total SO₃ to form H₂SO₄.

The foregoing use of undried atmospheric air for SO₂ gas formation and for interstage cooling in the catalytic conversion apparatus, permits elimination from the SO₃ production plant of sulfur melting and gas drying equipment and specially designed gas coolers between conversion stages. Hence, capital investment and maintenance costs in this phase of operation are greatly reduced. However, the SO₃ gas formed and recovered in conduit 32 is a wet gas and thus contains potential sulfuric acid mist forming constituents. As is well known in the art, when once formed acid mist cannot be removed from the gas stream by normal types of absorption procedure, goes thru the process unchanged, and causes a plant stack exit or "flag" which at times may be so objectionable as to require closing down of the plant.

Oleum is customarily made by countercurrent contact of SO₃ gas and oleum liquor under conditions such as to effect absorption of SO₃ out of the gas and to increase the dissolved SO₃ content of the oleum liquor to make an oleum product of sought for strength. Because of the high vapor pressure of SO₃ gas over oleum, absorption of SO₃ in the oleum liquor must be effected at relatively low temperatures. For example, in typical practice for making say 40% oleum from a representative 8% by volume SO₃ gas, such SO₃ gas is cooled down from the 700-800° F. exit temperature of the SO₂ converter system to about 180° F. prior to introduction of SO₃ gas into the bottom of the oleum production zone, and in the manufacture of a 20% oleum such contact system exit gas is cooled to about 250° F. Thus, in any case the converter exit gas is cooled down over such a broad temperature range that if such SO₃ gas were a wet gas, intolerable quantities of sulfuric acid mist would be formed, both during the cooling of the gas and at the point of first contact of the gas with the cool oleum liquor in the oleum production zone. Hence, the prior practice has been to form a dry contact system exit gas, so as to avoid the acid mist difficulty, which operation requires the use in the SO₃ production plant of the expensively constructed and maintained drying and heat transfer equipment.

The present invention affords an easily controllable procedure for making oleum from a wet SO₃ gas, and at the same time completely eliminates or at least reduces the formation of acid mist to an unobjectionable minimum. The invention thus makes it possible to take advantage of the reduction of capital investment and operating costs permissible in a plant which produces

a wet SO₃ gas at the exit of the converter system.

Practice of the invention involves contacting the hot wet SO₃ gas exiting the converter system with oleum liquor under certain conditions of temperature and oleum strength which effect condensation out of the gas stream as H₂SO₄ of all of the H₂O contained in the gas stream, bring about formation of a substantially dry SO₃ gas suitable for use in the production of oleum, and at the same time minimize formation of acid mist. Such operation may be carried out in a packed contacting zone as in tower 35, thru which zone the SO₃ gas and dispersed oleum liquor are flowed in countercurrent relation. In accordance with the invention, it has been found that the foregoing objects may be accomplished if (a) the wet SO₃ gas is introduced, at temperature above the dewpoint thereof, into countercurrent contact with oleum, (b) the oleum is maintained at the point of first contact of oleum with incoming wet gas at temperature not less than 300 and not more than 400° F., and (c) the oleum fed to the contacting zone for the contacting operation is cooler than but is of substantially the same composition as the oleum discharged from the contacting zone. Thus, the preferred embodiment of the invention comprises continuously introducing a stream of wet SO₃ gas, at temperature above the dewpoint thereof, into a gas-oleum liquor contacting zone, continuously introducing oleum into said zone, passing the gas and the oleum thru the zone in countercurrent flow relation, continuously discharging oleum from the zone, cooling the oleum and reintroducing cooled oleum into the contacting zone without change of composition, and controlling temperature and quantity of reintroduced oleum so as to maintain the oleum at the point of its first contact with incoming wet gas at temperature not less than 300° F. and not more than 400° F.

In starting up the process with respect to operation of the condenser-drier 35 of the drawing, the system comprising cooler 45, tower 35 and pipe connections 44 and 51 is filled with oleum of any strength above the sulfuric acid monohydrate point, i. e. sulfuric acid containing at least some dissolved SO₃, and preferably with oleum containing not more than about 5% free SO₃, i. e. 5% oleum. Cooler 45 is designed to accomplish any desired degree of heat removal from the contained oleum within the limits required by operation of a particular tower 35, rate of circulation of oleum liquor over the tower being regulated by pump 50. While gas entering tower 35 thru inlet connection 33 should be at temperature above the dewpoint, as a practical matter, temperature should be well above the dewpoint, preferably not less than 600° F., and as a rule in the range of 700-800° F. Countercurrent contacting of gas and oleum in the packed contacting zone in the tower 35 proceeds, dry SO₃ gas is discharged from the top of the tower thru pipe 38, and oleum runs out of the bottom of the tower thru pipe 44 into cooler 45.

Assuming a given flow of hot wet SO₃ gas into the bottom of tower 35, in accordance with the invention it has been found that when the temperature and quantity of oleum fed into the top of tower 35 is such as to maintain the oleum at the point of first contact of oleum with incoming wet gas at temperature not less than 300° F. and not more than 400° F. (i. e. for practical purposes, an oleum temperature within the 300-400° F. range in tower outlet pipe 44), and when

the oleum effluent is cooled and returned without change of composition to the top of tower 35, all of the H₂O constituents of the incoming gas condense out as H₂SO₄, most of the SO₃ content of the incoming gas over and above that needed to unite with the H₂O to form H₂SO₄ is discharged from the top of the tower as a dry SO₃ gas, and formation of acid mist is prevented or minimized.

When operation is under way, assuming the introduction into the bottom of tower 35 of a wet SO₃ gas stream of fairly constant characteristics, the single gauge point of control of operation of the condenser-drier is maintenance of the 300-400° F. temperature range in the oleum in pipe 44. Such temperature regulation in turn is effected by control of the amount of heat removal from the oleum in cooler 45, or the rate of flow of oleum over the tower effected by pump 50, or both. By keeping the temperature in tower outlet pipe 44 as indicated, cooling the oleum and returning the cooled oleum without change of composition, all other features of operation of the condenser-drier maintain themselves automatically.

The low temperature limit of 300° F. is needed to prevent objectionable formation of acid mist. Temperature of about 400° F. should not be exceeded in order to retain at least some dissolved SO₃ in the liquor. The 300-400° F. temperature range inherently controls the oleum strength in pipe 44, such strength ranging from a maximum of about 5% for an oleum temperature in the lower portion of the 300-400° F. range, down to a practical minimum of about 0.6-1.0% oleum strength for an oleum temperature in the upper portion of the 300-400° F. range. Accordingly, other operating conditions being equal, for a given oleum temperature in pipe 44, the oleum discharged from the tower thru pipe 44 is maintained at a constant composition of relatively low dissolved SO₃ content. As this oleum, after cooling, is returned to the top of the tower, it will be seen that the oleum effluent of the tower and the oleum returned to the tower are of identical compositions, this feature being an important distinguishing characteristics of the present process. Since the purpose of operation of the condenser-drier is to make a dry gas having a maximum SO₃ concentration, it is preferred to operate the contacting zone as hot as possible while still maintaining the circulating liquor above the sulfuric acid monohydrate point. Further, the hotter the liquor effluent in pipe 44 the less is the tendency for acid mist formation.

Taking into consideration the quantity of oleum circulated over the tower, the cooling effected in cooler 45 need be no more than that necessary to maintain the 300-400° F. temperature range in tower outlet pipe 44. For a representative commercial size condenser-drier, it is preferred to introduce the oleum into the top of the tower at temperature of not more than 260° F. and usually less. The relation between the temperature of the oleum in outlet pipe 44 and the oleum fed into the top of the tower may be regulated by the amount of heat removal in cooler 45 and by the quantity of acid circulated over the tower.

During descent of the oleum liquor thru the upper portion of the contacting zone, oleum strength probably rises appreciably, but because of the increasing temperature gradient between the top and the bottom of the tower the dissolved oleum content decreases back toward the par-

ticular composition prevailing in discharge pipe 44. It will be understood that the H₂O entering the bottom of the condenser-drier unites with sufficient SO₃ to form 100% H₂SO₄, and in the lower part of the tower there is a continuous 100% H₂SO₄ formation which would be expected to reduce continuously the dissolved SO₃ strength of the oleum discharged from the tower. To the contrary, it has been found that the maintenance of the 300-400° F. temperature range in pipe 44 inherently creates in the lower part of the contact zone conditions which cause just enough absorption of SO₃ to bring the 100% H₂SO₄ up to the existing dissolved SO₃ working conditions. Accordingly, in the condenser-drier operation as practiced the only overall SO₃ absorption which takes place is that which fortifies the 100% H₂SO₄ constantly being formed up to the dissolved SO₃ content of the tower liquor effluent.

In the contacting zone of tower 35 there are two principal sources of heat, sensible heat of the hot incoming SO₃ gas and heat of formation of sulfuric acid. The condensing-drying operation effected is characterized by the fact that no net desorption of SO₃ takes place in the contacting zone. Hence, there is no heat utilized in causing net SO₃ desorption and, aside from radiation losses, all of the heat in the contacting zone corresponding with the net difference between the temperature and chemical composition of the gas in inlet pipe 33 and the gas in outlet pipe 39 is removed from the contacting zone by the oleum and is discharged from the system by the cooling carried out in cooler 45. This heat removal from the contacting zone and avoidance of SO₃ desorption by such heat removal are automatically taken care of by the single expedient of maintaining the temperature of the oleum in pipe 44 as indicated.

Representative operation of the condenser-drier and utilization of the resulting dry SO₃ gas for manufacture of oleum is as follows:

A wet SO₃ gas, contained by volume 7.0% SO₃ and 2% H₂O or 0.455 gram per cubic foot of water, i. e. enough water to unite with 28.6% of the total SO₃ to form 100% H₂SO₄, may be passed into the bottom of tower 35 at temperature of about 800° F. A good working temperature of the oleum in condenser-drier discharge pipe 44 is about 375° F. Hence, the amount of heat removal in cooler 45 and the rate of operation of pump 50 are chosen, according to the design of the particular tower being used, to control the temperature and quantity of the oleum fed into the top of the tower so as to maintain the oleum in pipe 44 at temperature of about 375° F. In this situation, the oleum in pipe 44 and the oleum fed into the top of the tower contain about 1.0% by weight of free SO₃, i. e. 1.0% oleum. Temperature of the oleum fed into the top of the tower thru pipe 51 may be about 250° F. There is then produced in gas off-take pipe 39 a dry gas having a temperature of about 250° F., and an SO₃ concentration by volume of about 5.0%. The "make" of 1.0% oleum in the circulating system of tower 35 is run thru line 53 into the cooler 61 of the e. g. 20% oleum production tower 62.

Design and construction of tower 62 may be the same as that of the packed oleum production towers known in the art. This tower includes at the top a gas outlet 64 and an oleum inlet 65, and at the bottom a gas inlet 67 and an oleum outlet 68 connected to cooler 61. The sulfuric

acid production tower 70 may be built the same as absorption towers customarily used in the manufacture of sulfuric acid from SO_3 ; this tower being provided with a cooler 71 with associated pump and piping necessary to effect circulation of acid over the tower.

Introduction of diluent into cooler 61 from lines 53 and 75, cooling and rate of liquor flow in the circulating system of tower 62 are regulated so that oleum of strength of about 18% and at temperature of about 135° F. is fed into the top of tower 62 thru pipe 65. Gas and liquor contacting in tower 62 is such that 20% oleum is discharged from the bottom of tower 62 by pipe 68 from which the oleum "make" of the entire process may be drawn off thru pipe 78. The gas stream leaving the top of tower 62 and passing thru pipe 64 into the bottom of sulfuric acid production tower 70 may be at temperature of about 135° F. and have an SO_3 concentration by volume of about 2.8%.

Whatever extraneous diluent may be needed in the process is introduced, as water or dilute sulfuric acid, thru line 80 into the acid circulating system of tower 70. The liquor cooling and circulating system of tower 70 is operated as is known in the art to produce say 99% strength sulfuric acid, and the "make" of tower 70 is passed thru line 75 into the cooler 61 of oleum production tower 62.

The process as described up to and including operation of the condenser-drier may be used in connection with production of sulfuric acid alone in which instance gas outlet pipe 39 of tower 35 may be connected directly to the gas inlet at the bottom of tower 70, and oleum line 53 may be connected to cooler 71 of tower 70. In this modification, the exit gas of pipe 39, at temperature of about 250° F. and containing 5.0% by volume of SO_3 is introduced into the bottom of tower 70 which is operated as known in the art to produce strong e. g. 99.5% sulfuric acid. The advantage of this mode of procedure is that sulfuric acid may be made from all of the SO_3 content of an initially wet SO_3 gas, by first condensing out the H_2O of the wet gas as H_2SO_4 , and then recovering the dry SO_3 as product sulfuric acid by means of a low temperature SO_3 absorption step. Since in this operation, temperature of the acid discharged from the tower 70 need not be higher than 140° F., it will be seen that corrosion caused by high temperature is avoided and it is possible to use less expensively constructed and maintained apparatus.

I claim:

1. The process for making substantially dry SO_3 gas from a wet gas containing SO_3 constituent and some but less H_2O constituent than needed to unite with all SO_3 present in said wet gas to form H_2SO_4 , which process comprises introducing a stream of said wet gas, at temperature above the dewpoint thereof, into a gas-oleum contacting zone, introducing hereinafter defined oleum having at least some dissolved free SO_3 into said zone, passing said gas and said oleum thru said zone in countercurrent flow relation, discharging oleum from said zone, cooling said oleum and reintroducing said cooled oleum into said zone without change of composition, controlling temperature and quantity of reintroduced oleum so as to maintain said oleum at the point of first contact of oleum with incoming wet gas at temperature not less than 300° F. and not more than 400° F., whereby H_2O is condensed out of the gas stream as H_2SO_4 and formation of acid mist is minimized, and the free SO_3 strength of the oleum discharged from said zone is substantially the same as the free SO_3 strength of the oleum introduced into said zone; and discharging substantially dry SO_3 gas from said zone.

2. The process for making substantially dry SO_3 gas from a wet gas containing SO_3 constituent and some but less H_2O constituent than needed to unite with all SO_3 present in said wet gas to form H_2SO_4 , which process comprises introducing a stream of said wet gas, at temperature above the dewpoint thereof, into a gas-oleum contacting zone, introducing oleum having at least some dissolved free SO_3 into said zone, passing said gas and said oleum thru said zone in countercurrent flow relation, discharging oleum from said zone, controlling temperature and quantity of oleum introduced into said zone so as to maintain said oleum at the point of first contact of oleum with said incoming wet gas at temperature not less than 300° F. and not more than 400° F., said oleum introduced into said zone being cooler than and having the same composition as the oleum discharged from said zone, whereby H_2O is condensed out of the gas stream as H_2SO_4 and formation of acid mist is minimized, and the free SO_3 strength of the oleum discharged from said zone is substantially the same as the free SO_3 strength of the oleum introduced into said zone; and discharging substantially dry SO_3 gas from said zone.

3. The process for making substantially dry SO_3 gas from a wet gas containing SO_3 constituent and some but less H_2O constituent than needed to unite with all SO_3 present in said wet gas to form H_2SO_4 , which process comprises introducing a stream of said wet gas, at temperature above the dewpoint thereof, into a gas-oleum contacting zone, introducing hereinafter defined oleum having at least some dissolved free SO_3 into said zone, passing said gas and said oleum through said zone in countercurrent flow relation, discharging oleum from said zone, cooling said oleum to temperature not higher than 260° F. and reintroducing said cooled oleum into said zone without change of composition, controlling temperature and quantity of reintroduced oleum so as to maintain said oleum at the point of first contact of oleum with incoming wet gas at temperature not less than 300° F. and not more than 400° F., whereby H_2O is condensed out of the gas stream as H_2SO_4 and formation of acid mist is minimized, and the free SO_3 strength of the oleum discharged from said zone is substantially the same as the free SO_3 strength of the oleum introduced into said zone; and discharging substantially dry SO_3 gas from said zone.

4. The process for making oleum which comprises burning sulfur material with undried air to form a hot, moist SO_2 gas, cooling said moist gas to but not below initial conversion temperature, catalytically oxidizing the SO_2 of said moist gas to SO_3 in a multi-stage conversion operation, effecting the required cooling of the gas stream between stages by introduction between stages of undried air, continuously introducing the resulting wet gas containing SO_3 and H_2O constituents, at temperature above the dewpoint thereof, into a gas-oleum contacting zone, continuously introducing hereinafter defined oleum having at least some dissolved free SO_3 into said zone, passing said gas and said oleum thru said zone in countercurrent flow relation, continuously dis-

charging oleum from said zone, cooling said oleum and reintroducing said cooled oleum into said zone without change of composition, controlling temperature and quantity of reintroduced oleum so as to maintain said oleum at the point of first contact of oleum with incoming wet gas at temperature not less than 300° F. and not more than 400° F., whereby H₂O is condensed out of the gas stream as H₂SO₄ and formation of acid mist is minimized, and the free SO₃ strength of the oleum discharged from said zone is substantially the same as the free SO₃ strength of the oleum introduced into said zone; continuously discharging substantially dry SO₃ gas from said zone, and continuously introducing said dry SO₃ gas into an oleum production zone regulated to absorb SO₃ and form oleum.

5. The process for making sulfuric acid which comprises burning sulfur material with undried air to form a hot, moist SO₂ gas, cooling said moist gas to but not below initial conversion temperature, catalytically oxidizing the SO₂ of said moist gas to SO₃ in a multi-stage conversion operation, effecting the required cooling of the gas stream between stages by introduction 20 between stages of undried air, continuously introducing the resulting wet gas containing SO₃ and H₂O constituents, at temperature above the dewpoint thereof, into a gas-oleum contacting zone, continuously introducing hereinafter defined oleum having at least some dissolved free SO₃ into said zone, passing said gas and said oleum thru said zone in countercurrent flow relation, continuously discharging oleum from said zone, cooling said oleum and reintroducing said 25 cooled oleum into said zone without change of composition, controlling temperature and quantity of reintroduced oleum so as to maintain said oleum at the point of first contact of oleum with incoming wet gas at temperature not less than 300° F. and not more than 400° F., whereby H₂O is condensed out of the gas stream as H₂SO₄ and formation of acid mist is minimized, and the free SO₃ strength of the oleum discharged from said zone is substantially the same as the free SO₃ strength of the oleum introduced into said zone; and discharging substantially dry SO₃ gas from said zone.

5 free SO₃ strength of the oleum introduced into said zone; continuously discharging substantially dry SO₃ gas from said zone, and continuously introducing resulting dry SO₃ gas into a sulfuric acid production zone regulated to absorb SO₃ and form sulfuric acid.

6. The process for making substantially dry SO₃ gas from a wet gas containing SO₃ constituent and some but less H₂O constituent than needed to unite with all SO₃ present in said wet gas to form H₂SO₄, which process comprises introducing a stream of said wet gas, at a temperature not less than 600° F., into a gas-oleum contacting zone, introducing hereinafter defined oleum containing at least some but not more than about 5% free SO₃ into said zone, passing said gas and said oleum through said zone in countercurrent flow relation, discharging oleum from said zone, cooling said oleum to temperature not higher than 260° F. and reintroducing said cooled oleum into said zone without change of composition, controlling temperature and quantity of reintroduced oleum so as to maintain said oleum at the point of first contact of oleum with incoming wet gas at temperature not less than 300° F. and not more than 400° F., whereby H₂O is condensed out of the gas stream as H₂SO₄ and formation of acid mist is minimized, and the free SO₃ strength of the oleum discharged from said zone is substantially the same as the free SO₃ strength of the oleum introduced into said zone; and discharging substantially dry SO₃ gas from said zone.
